UNITED STATES PATENT OFFICE.

PERRY BARTLETT, OF SPOKANE, WASHINGTON.

AXLE-LUBRICATOR.

SPECIFICATION forming part of Letters Patent No. 668,081, dated February 12, 1901.

Application filed April 19, 1900. Serial No. 13,556. (No model.)

To all whom it may concern:

Be it known that I, PERRY BARTLETT, a citizen of the United States, residing at Spokane, in the county of Spokane and State of Washington, have invented new and useful Improvements in Axle-Lubricators, of which the following is a specification.

My invention relates to improvements in axle-lubricators; and it consists in a certain novel construction the utility and advantages of which will be fully understood from the following description and claims when taken in conjunction with the annexed drawings, in which—

Figure 1 is a view, partly in elevation and partly in section, illustrating a wagon-axle equipped with my improvements. Fig. 2 is a top plan view of the same.

Referring by letter to the said drawings, A is a wagon-axle provided with suitable spindles *a*, and B B are the reservoirs or lubricant-receptacles of my improvements, which are preferably provided with apertured ears *b* and connected to the rear side of the axle by screws *c*, passed through said ears, as shown. The said reservoirs or lubricant-receptacles are designed to be filled in any preferred manner with axle-grease or other suitable lubricant and are connected at their outer ends to tubes *C*, which lead to and through the spindles *a* to a point at the upper side and about midway the length thereof, as shown.

D D' are followers which are arranged and adapted to be moved in the reservoirs or receptacles B and have for their purpose to expel the grease or other lubricant from the said reservoirs and force the same through the tubes *C* to the axle-spindles as it is needed thereon. The said followers D D' have stems *d d'*, respectively, which extend through the inner heads of the reservoirs and are threaded, as shown—that is to say, the stem *d* of follower D is provided with left-hand threads *e*, while the stem *d'* of follower D' is provided with right-hand threads. The follower-stems extend through suitable guides *g* on axle A and are connected after the manner shown by a turnbuckle *E*, which is provided at one end with right-hand threads and at its opposite end with left-hand threads. When this turnbuckle is turned in one direction, it is obvious that the followers D D' will be moved

inwardly or toward each other, while when it is turned in the opposite direction the followers will be moved outwardly.

In practice the receptacles or reservoirs B are charged with axle-grease or other lubricant while the followers D D' are at or adjacent to the inner heads of the receptacles, and then as lubricant is needed on the axle-spindles the turnbuckle *E* is turned to move the followers outwardly or in the direction indicated by arrows in Fig. 1. When the followers are thus moved outwardly, the grease or lubricant is forced through the tubes *C* to the axle-spindles and is spread over the same by the rotation of the wheels (not shown) thereon.

It will be readily appreciated from the foregoing that the receptacles B are adapted to hold a large quantity of axle-grease or other lubricant without liability of dust, grit, or other foreign substance being commingled therewith and that a greater or less amount of the lubricant may be forced to the axle-spindles as the conditions require.

It will also be observed that my improvements are simple and inexpensive in construction, are susceptible of ready attachment to a wagon or other axle, and are adapted to be quickly and easily operated for the purpose described.

It is obvious that when desired the lubricant receptacles or reservoirs might be fixed on a support other than the axle without departing from the scope of my invention.

Having thus described my invention, what I claim is—

1. In an axle-lubricator, the combination of an axle having suitable spindles, lubricant reservoirs or receptacles fixed at a suitable distance apart, conduits leading from said receptacles or reservoirs to the axle-spindles, followers arranged in the receptacles or reservoirs, and having stems provided with right-hand threads and left-hand threads, respectively, and a turnbuckle interposed between the stems of the followers and having threaded apertures receiving the same, substantially as specified.

2. In an axle-lubricator, the combination of an axle having spindles, lubricant reservoirs or receptacles fixed on the axle at a suitable distance apart, tubes leading from the outer ends of the reservoirs to and through

the axle-spindles to the surfaces thereof, followers arranged in the receptacles or reservoirs and having stems extending through the inner threads thereof, and provided with right-hand threads and left-hand threads, respectively, and a turnbuckle interposed between the stems of the followers and having

threaded apertures receiving the same, substantially as specified.

PERRY BARTLETT.
